POSTURE BED STRUCTURE

Robert R. Freund, Mount Carmel, Ill.

Application March 29, 1939, Serial No. 264,766

12 Claims. (Cl. 5—69)

This invention relates to a posture bed. The chief object of this invention is to provide a bed of articulated character, whereby the same may have its several parts moved into various positions necessitated by the patient's particular condition.

Another object of the invention is to provide a readily accessible arrangement whereby the patient may personally adjust portions of the bed structure to suit his convenience.

Another object of the invention is to provide a structure which is not only manually adjustable but may be power adjustable as well.

Another object of the invention is to arrange a bed that can be collapsed, as it were, so that the entire bed as a single unit can be moved from room to room in a hospital or from a rental agency into a home by merely collapsing the entire bed so that it will pass sidewise through the several doors and without requiring dismantling.

Another object of the invention is to provide for the support of articles such as a book or tray for the patient's convenience.

Another object of the invention is to provide for the support of legs in a lithotomy position.

The chief feature of the invention consists in embodying in a bed structure of articulated character the several mechanisms whereby the bed and portions associated therewith may be adjusted, operated or utilized as necessity or convenience may require.

This application is a substitute for a similarly entitled application Serial No. 115,272 filed December 11, 1936, inadvertently abandoned and in which a petition for revival was denied.

The full nature of the invention will be understood from the accompanying drawings and the following description and claims:

In the drawings,

Fig. 1 is a top plan view of a bed structure embodying the invention.

Fig. 2 is a side elevational view thereof, including tray and leg holder attachments, portions of the bed being shown in other than a horizontal position.

Fig. 3 is a transverse sectional view looking toward the head of the bed when the head portion of the bed structure is horizontal, and including more especially, the motive type power and the evacuation associated mechanism and is taken on line 3—3 of Fig. 1 and in the direction of the arrows.

Fig. 4 is a more or less diagrammatic side elevation of a modified form of the invention.

Fig. 5 is a similar view of a portion of a still further modified form of the invention.

Fig. 6 is a perspective view of the evacuation vessel shown in Fig. 3.

Fig. 7 is a top plan view of the mattress structure shown more especially in Fig. 3.

In the drawings 10 indicates supporting leg structures terminating in suitable casters 12, or the like, engaging the floor and having a detachable, and herein telescopic, connection with projecting portions 13 of a main frame or base, including two side plates 14 transversely united together by the tie bars or equivalent structures 15. The legs are detachably associated in said telescopic relation as indicated at 16. The main frame is shorter than the bed proper.

Extending from plate to plate is a shaft 17 rigid with which is a winding drum 18 at each end adjacent the plate. The shaft projects 20 through the plate and terminates in a squared or equivalent end 19 adapted to detachably receive a crank handle 20.

Pivotedly mounted near the upper and rearward ends of the plate structures 14 and at 21, 25 is a U-shaped head portion of the bed structure 22 which includes a plurality of parallel, spaced, flexible mattress supporting metallic strips 23 yieldingly associated at each end as at 24 with the spring supporting member 25. The two plates 14 support continuations of the frame 22 as at 26 and a plurality of similar strips 23 are provided and similarly yieldingly mounted as at 24 to members 27.

Herein a plurality of intermediate and relatively short strips 28 are provided, each of which is yieldingly mounted at one end as at 29 to the adjacent member 27 and the opposite end is suitably secured to a longitudinally directed member 30, the same extending transversely of 40 the ends of the strips 28 and 23 and being secured at opposite ends to the two immediate adjacent members 23. This forms an opening indicated generally in Fig. 1, by the numeral 31. This portion of the bed structure is relatively stationary.

Hingedly supported at 32 is a continuation 33 of the bed frame structure and hingedly connected thereto is a U-shaped extension 34, the two being hingedly connected together as at 35 50 by a combination pivotal tongue and groove connection. Bed frame members 33 are provided with spring support members 36 and the U-shaped foot portion of the bed frame 34 is provided with the spring support members 37. Each 55 of these bed portions is provided with parallel

metallic strips 23 yieldingly connected to said respective members 36 and 37 at opposite ends by the springs 24. The foregoing constitutes the mattress support and is substantially continuous except for the opening 31 to which reference will be had hereinafter.

Pivots supported upon the interior of each of the base plates 14 as at 38 is a lever arm 39 terminating at one end in a cam portion having the elevating portion 40 and the maintaining portion 41, one being a continuation of the other. Each of the members 39 at their other ends supports a shaft 42 which extends through arcuate slots 43 in the base plates 14, said slots being concentric with the pivots 38. The projecting ends of the shaft are squared as at 44 to receive the handle 20 for manual operation for a purpose hereinafter to be set forth more fully.

The extreme end of each of levers 39 is bifurcated as at 45 and apertured as at 46 to receive a threaded post 47 that mounts a yoke 48 that pivotally supports at 49 a grooved roller 50. The grooved roller bears on the undersurface of the frame portion 33. When the crank 20 is positioned on shaft 17 and rotated, the winding drums 18 are rotated therewith and the cables 51, connected at one end to the drum and at the opposite end as at 52 to the extension 53 of the frame 22, serve to tilt upwardly in clockwise direction the head portion of the bed frame. 30

An extension 54 in alignment with each side portion of the frame 22, terminates in a roller 55 that bears upon the cam portion 40 of the lever 39. In this elevating movement of the head portion, the cam construction is tilted which elevates the bed frame portion 33, as shown in Fig. 2, and to a corresponding degree determinable by the contour of the cam.

The foot portion 34 is supported by an arm 56 that pivotally supports a grooved roller 57, bearing on the underface of the side portion of the U-shaped foot frame portion of the bed frame 34. The tangential upper plane with respect to rollers 57 corresponds to the lower plane of the bed frame when the portions are in horizontal alignment.

Continued rotation of the shaft 17 permits the roller 55 to travel upon the portion 41 of the lever 39 and since this portion is concentric with the axis 21, no further tilting movement of the intermediate frame portion (not the stationary intermediate frame portion) and the foot portion occurs.

Near each end of the shaft 42 the same carries a worm 58 which meshes with the worm wheel 59 having threaded connection with the threaded member 47. Thus, rotation of the shaft 42 by the crank 20 applied to either squared end 44 will serve to actuate the worm and worm wheel mechanisms and thus serve to elevate or lower, as the case may be, depending upon the direction of rotation of the shaft 42, the roller supports 50 upon which the bed frame portions 33 bear. In this manner the relative positioning of members 33 may be adjusted with respect to the position of portion 22. This provides for a considerable flexibility in the variation in the respective positions of the portions of the posture bed.

Another adjustment to secure a similar result and more especially with reference to the foot portion of the bed frame 34, is shown more especially in Fig. 2. Arm 56 at each side of the bed is slidably supported in the ways 60, carried by the base plate 14. Pivots mounted as at 61

is a pinion 62 which meshes with the rack portion 63 of the horizontal portion 56a of the arm 56. The shaft rigid with the pinion or gear 62 extends through the plate 14 and mounts a crank handle 64. For clearness, certain of this mechanism previously described, is omitted from Fig. 1.

Positioned at each side of the posture bed and carried by the base plates 14 are the sockets 65 which telescopically receive the standard portion 66 of a tray or book support member 67, the supporting portion proper being indicated by the numeral 68 and having a longitudinally adjustable connection as at 69. This connection also permits the tray or book support to be tilted with respect to the horizontal plane. The height of the horizontal portion 67 may be adjusted relative to the bed and retained in the adjusted position by the hand wheel locking arrangement 70.

There is also provided at each side of the bed on base plates 14 another pair of tubular sockets 71 which receive the vertical portions 72 of a leg holder having the horizontal portions 73 and the vertical portions 74. A similar hand wheel operated locking device 75 is adapted to rigidly secure the leg holder attachment in the desired adjusted position, which may be varied for angularity, in a horizontal plane as well as for elevation with respect to the bed. These devices are highly desirable for use in obstetrical cases.

The foregoing constitutes the manual form of the invention, wherein the nurse may manipulate the various mechanisms for adjusting the bed structure.

Whenever it is desired, the patient may also manipulate the bed structure and while lying therein. Reference will be had now more especially to Fig. 2. In this figure, 76 indicates a bevel gear rigid with the shaft 17. Meshing therewith is a bevel pinion 77 carried by shaft 78 rotatably supported in bearings 80 carried by the adjacent base plate 14. The upper end of the shaft 78 terminates in a universal joint 79, one portion of which is connected to a shaft 81 having a socket 82 for the reception of a crank or handle structure 83, positioned immediately at one side of the bed and slightly above the plane of the bed when the mattress is applied thereto. The friction between the several parts and gears 76 and 77 is sufficient to retain the head portion in the adjusted and elevated position. With this structure, the patient may, if sufficiently convalescent, personally adjust portions of the bed to the position which will give the patient the greatest ease and comfort.

Reference will now be had more especially to Figs. 3, 6 and 7. It will be recalled that members 30 are united to the adjacent ends of the flexible metal strips 28. Depending from the members 30—see Fig. 3—which are shown as angle iron structures, are the spaced plates 84 connected at their base by the transverse portion 85. A mattress includes one section 86 substantially rectangular in form, and another section 87, U-shaped in form, having a recess 88 therein substantially corresponding to the opening 31, see Fig. 1, in the spring frame. This opening is closed by a mattress insert or plug 89—see Fig. 7—which bears upon a plate or suitable support 90 which in turn bears upon the rimmed mouth 91 of a U-shaped member 92, flexibly supported by the spring 93 upon a rack type stem or the post 94, the latter extending through the aperture 85a in the portion 85 which guides said post. 70

In brackets 95 and 95a is rotatably supported a

shaft 96 which mounts a spur gear 97 meshing with the rack type post 94. A pinion 98 on the end of the shaft 96 meshes with pinion 99 carried by a vertical shaft 100 rotatably supported in the bracket 95 at its lower end and in bracket 101 in its upper end, the latter being carried by the adjacent frame member 84.

The upper end of the shaft 100 terminates in a worm wheel 102 which meshes with a worm 103 carried by shaft 104 one end of which is mounted in the bracket 101 and the other end of which is mounted in the bracket 105 carried by the adjacent side frame 14. The projecting end of the shaft 104 mounts a bevel gear 106 which meshes with bevel gear 107 on the end of a shaft 108, the upper end of which is adapted to receive a crank 109. A vessel 110 having the hand engageable portion, such as opening 111, and the open mouth 110a is adapted to be received by the vessel carrying frame 92 having the open but rimmed mouth 91.

It will be noted—see Fig. 3—that the mattress section or block 89 is supported in coplanar alignment with mattress portions 86 and 87 by the plate 90 and the vessel supporting structure herein just described. When a patient can be moved from one side of the bed to the other, the mattress block may be removed upwardly and then the patient returned into central bed position and when in that position, the buttocks of the patient will register with the vessel and if desired to ease the patient, the movable portions of the bed may be adjusted into a position other than horizontal and the patient may then evacuate at ease. Following this, the patient may be lowered into horizontal position, moved to the right or left and the mattress section 89 replaced. Thereafter the hospital attendant or the nurse may remove the vessel 110 from the back of the bed.

When the patient cannot be moved and evacuation is necessary, the nurse or attendant may operate the crank 109 to lower the vessel support until the mattress section 89 lies below the plane of the spring portion 28 and then the mattress section 89 may be removed in the same manner that the vessel was removed. With such removal, of course, the supporting portion 90 is also removed. With this removal, then the crank is again actuated to elevate the vessel support with the vessel therein so that the rim portion registers with the top edge of or is coplanar with the upper surface of the mattress sections 86 and 87. It, of course, is to be understood that in the previously mentioned operation relative to evacuation, the crank 109 is preferably elevated to raise the support 90 and mattress section 89 upwardly until both may be removed, leaving the rimmed edge 91 of the vessel support in the aforementioned coplanar relationship with respect to the mattress sections 86 and 87.

Either of the foregoing operations, of course, may be performed with the patient in the sitting position.

For the purpose of clearness, it will, of course, be understood that various anti-friction bearings will be utilized, wherever such anti-friction type of mounting is desired or necessary. Furthermore it is to be understood the various types of gearing herein illustrated are merely illustrative examples of gearing which may be employed in this manner.

Whenever it is desired to provide for power manipulation, the same herein is illustrated as 75

applied to the movement of the articulated portions of the bed frame, although by the addition of other motive means or a selective clutch construction, the motive power may be applied to each of the manually operable adjustable mechanisms.

In the several figures, 112 indicates an electric motor which operates through a speed reducer, if desired, or directly, a worm 113 meshing with the worm wheel 114 rigid with the shaft 17 that carries the cable winding drums 18. Supply lines 115—116 may be controlled by a suitable power switch 117 and are connected by a flexible cable 118a and 118b to the motor. A push button or like, normally open switch 119 is adapted upon closure, if the switch 117 is closed or the motor extension cord connector is plugged into a wall or floor outlet, to close the motor circuit as long as the button is depressed and thus the shaft 17 rotates in the desired direction.

Whenever it is desired to reverse the rotation for lowering, for example, the reverse switch member 120 is actuated and the motor lowers the posture bed. Limit switches, as are well understood in the electrical motor industry may be associated with such a device. The motor, of course, is of reversible character.

In Fig. 4 a slightly modified form of the invention is diagrammatically illustrated and herein in 130 indicates a side plate similar to base plate 14. 131 represents the side portion of the U-shaped head frame, 132 the supporting leg structure having the caster 133, or the like, and in this form of the invention, the projecting arm 134 of the plate 130 is the equivalent of the projecting arm 56, previously described.

Herein a pair of brackets 135 on each rearward member 132 mounts a sprocket 137 and 138 connected by a chain 139. A crank 140 on the common transverse shaft 141 is adapted to move the chains one direction or the other and movable therewith are members 141 carrying rollers 142 pivoted at 143 and constituting a support for the head portion of the bed frame.

45 A link 144 is pivotally connected as at 145 to the head frame 131 and is pivotally connected at 136 to the bracket 141. Thus, movement of the hand crank 140 serves to raise or lower the head frame, depending upon the direction of crank rotation. It is also to be understood the construction is duplicated on the other member 132 and the shaft 141, which extends through the upper bracket 135 and mounts the cogs 137, extends from one side structure to the other and the crank 140 may be associated with either projecting end of the shaft 141. The head frame structure portion is pivoted at each side at 148 on the side frame or base plate 130 and includes the arm and cam portion 149 as well as the pin stop 150.

60 The intermediate tiltable bed frame portion comparable to portion 33, is indicated by the numeral 151 and is pivoted at 152. The same in turn at its opposite side is pivoted at 153 to the U-shaped foot frame structure portion 154, similar to the foot frame structure 34. To obtain the adjustment comparable to the adjustment obtained by the longitudinal movement of member 56a by the rack and pinion arrangement, there is provided herein a slot 155 in each arm 134 projecting from the base plates 130 and an adjustable fulcrum member 156 rides therein.

65 The same is adjustably associated with the member 154 through the medium of the slot 157. The member 151 includes a depending arm 158

70

having an aperture 159 therein adapted to receive a bolt 160 which may be positioned in any one of the arcuately spaced openings 161 carried by the cam or actuating plate 162 also pivoted at 152.

The cam plate 162 has the tilting portion 163 and the concentric radial or holding portion 164. The cam plate also slidably supports by means of the spaced pins 165 a latch member 166 having elongated, aligned slots 167 therein, the angular end portion 168 associated with the pin 150 and a pawl engaging opposite end 169.

The opposite end of the cam plate has an arcuate face 170 and a bevel portion 171 adapted to be engaged by the operative end 172 of a pawl or locking dog 173 constrained into cam plate engagement by the spring 174 mounted on the plate 130, as shown. It is believed the operation of the device and the functioning of the pawl and latch arrangement is self evident from the foregoing description and the explanation following.

In the positive elevation of member 131, portion 149 engages face 163 and moves member 162 to the right which in turn tilts member 151 upwardly and member 154 downwardly when positioned as shown. In this movement face 170 rides pawl 173 in opposition to spring 174, same serving as a latch or stop by engaging shoulder 171. When member 151 is lowered to prevent undue dropping thereof, said pawl being prevented from undue dropping by member 169 through end 168 and pin 150 when member 131 is lowered to horizontal position.

In Fig. 5 a modified form of the invention is diagrammatically illustrated. In this figure, 180 indicates the base or side plate, 181 the head portion of the bed frame pivoted as at 182 to the side plate. It also includes the cam portion 183, the cooperating pin 184 and the member 185 35 is associated therewith in the same manner that 168 in Fig. 4 is associated with the pin 150 in said figures. Herein the base plate is supported by the leg 186 suitably supported by caster 187 and the jointed link construction 188 and 189 is 40 pivotally connected at one end as at 190 to the leg member 186 and at 191 to head member 181. The two links are pivotally connected together as at 192 and to the pivot is secured the cable 193 which is windable upon the drum 194, operable 45 by the crank 195, the shaft 196 carrying the drums being supported in the brackets 197 carried by the legs 186.

The bed previously described is arranged so that the head portion supports the head and 55 chest of the patient, the stationary intermediate portion supports the hips of the patient, the movable intermediate portion supports the thighs of the patient, and the foot portion supports the lower limbs and feet of the patient.

For obstetrical purposes, all bed portions are in horizontal alignment except the foot portion which can be adjusted to hang vertically downwardly or substantially in that position.

For genital-urinary purposes, the foot portion 65 is similarly positioned but the intermediate movable portion is elevated to the desired angle.

When necessary the head portion, see Fig. 2, need not be tilted when the other portions are positioned as last mentioned.

Positions similar to that illustrated in Fig. 2 are suitable for relaxation and rest, eating, reading, writing and defecation, and suitable for pneumonia and bad heart conditions of patients.

The bed is readily movable as an entirety 75

so that the patient (if ambulation is impossible) may sit up and be moved to the operating room, X-ray department, solarium or the like, as desired or required.

For leg fracture cases, the head portion only is tilted and the thighs or legs are immobilized or held in traction.

The various positions are all obtainable with the present invention, or slight modifications thereof as will be readily apparent to persons skilled in this art.

This pedestal bed may be readily collapsed to permit passage through relatively narrow openings without necessitating bed dismantling.

It will also be self apparent that various forms of cooperative connections can be effected, departing from the specific disclosures illustrated herein, by which the several movable portions are simultaneously movable through the interconnection and movement of but one movable portion of the bed.

While the invention has been described in great detail in the foregoing specifications, it is to be understood that description and the drawings illustrating the same, are to be considered as illustrative and not restrictive in character. The various modifications herein disclosed by description and drawings as well as those suggested and others which will readily suggest themselves to persons skilled in this art, are all considered to be within the broad scope of this invention, reference being had to the appended claims.

The invention claimed is:

1. The combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former.

2. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former, the last mentioned connecting means being of adjustable character for obtaining variable degrees of tilting of the intermediate movable sec-

tion for any selected tilted position of the first mentioned end section.

3. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former, the last mentioned connection means including a cam and follower connection including a pair of cooperating elements, one being a rigid extension of said first mentioned bed section and movable therewith, the other element constituting the sole connection to the remainder of the connecting means, the cam element including an eccentric portion and a concentric portion forming a continuation thereof and engageable by the follower.

4. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former, the last mentioned connection means including a cam and follower connection including a pair of cooperating elements, one being a rigid extension of said first mentioned bed section and movable therewith, the other element constituting the sole connection to the remainder of the connecting means, the cam element including an eccentric portion and a concentric portion forming a continuation thereof and engageable by the follower, said follower being of the roller type.

5. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate movable section, the operative support engagement being such that the said other end section may be coplanar with the first mentioned end section when the latter is not tilted and permitting relative movement between the adjustable means and the second mentioned end section in the tilting movement of the intermediate sec-

tion, and means operatively connecting the first mentioned end section and the intermediate movable section for movement of the latter simultaneously with the movement of the former, the last mentioned means at one end including an adjustable arrangement for obtaining variable degrees of tilting of the intermediate movable section for any selected tilted position of the first mentioned end section and at the opposite end including a cam and follower connection including a pair of cooperating elements, one being a rigid extension of said first mentioned bed section and movable therewith, the other element constituting the sole connection to the remainder of the connecting means, the cam element including an eccentric portion and a concentric portion forming a continuation thereof and engageable by the follower, said follower being of the roller type.

6. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former, the last mentioned means at one end including an adjustable arrangement for obtaining variable degrees of tilting of the intermediate movable section for any selected tilted position of the first mentioned end section and at the opposite end including a cam and follower connection including a pair of cooperating elements, one being a rigid extension of said first mentioned bed section and movable therewith, the other element constituting the sole connection to the remainder of the connecting means, the cam element including an eccentric portion and a concentric portion forming a continuation thereof and engageable by the follower.

7. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former, the last mentioned connecting means being of adjustable character for obtaining variable degrees of tilting of the intermediate section for any selected tilted position of the first mentioned

end section, the adjustable character of the connecting means being of gear type.

8. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate 10 movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former, the adjustable means being of gear type.

9. In an invalid bed, the combination with a supporting base and an articulated bed structure including at least three tilttable bed forming 25 sections, two of the sections having adjacent end to end pivotal connection, of means for tilting one end section, adjustable means operatively supporting the opposite end section and remote from its pivotal connection to the intermediate 30 movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first 35 mentioned end section and the intermediate movable section for movement of the latter simultaneously with the movement of the former, the last mentioned connecting means being of adjustable character for obtaining variable degrees of tilting of the intermediate section for any selected tilted position of the first mentioned end section, the adjustable character of the connecting means being of gear type, the first mentioned adjustable means also being of gear type, the gearing being of dissimilar character.

10. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate 55 movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first 60

mentioned end section and the intermediate movable section for movement of the latter simultaneously with the movement of the former, the last mentioned connecting means being of adjustable character for obtaining variable degrees of tilting of the intermediate movable section for any selected tilted position of the first mentioned end section, and of pin and multiple socket type with the addition of latch and catch means for the purpose described.

11. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate 15 movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first mentioned end section and the intermediate movable section for movement of the latter simultaneously with the movement of the former, the adjustable means including an elongated slot in the base, and an elongated slot in the second mentioned end section, and means common to both slots for the purpose described.

12. In an invalid bed, the combination with a supporting base and an articulated bed structure including at least three tilttable bed forming sections, two of the sections having adjacent end to end pivotal connection, of means for tilting one end section, adjustable means operatively supporting the opposite end section and remote from its pivotal connection to the intermediate 20 movable section, the operative support engagement being such that the said other end section may be coplanar with the first mentioned end section when the latter is not tilted and permitting relative movement between the adjustable means and the second mentioned end section in the tilting movement of the intermediate section, and means operatively connecting the first 25 mentioned end section and the intermediate movable section for movement of the latter simultaneously with the movement of the former, the last mentioned connecting means being of adjustable character for obtaining variable degrees of tilting of the intermediate section for any selected tilted position of the first mentioned end section, and of pin and multiple socket type with the addition of latch and catch means for the purpose described, said adjustable means including an elongated slot in the base, and an elongated slot in the second mentioned end section, and means common to both slots for the purpose described.

ROBERT R. FREUND.
